United States Patent Office

Des. 213,346
Patented Feb. 18, 1969

213,346

DRESSING MIRROR

Norman J. Mercer, New York, N.Y., assignor to The Englishtown Corporation, New York, N.Y., a corporation of New York

Filed Oct. 26, 1967, Ser. No. 9,175

Term of patent 14 years

U.S. Cl. D86—10

FIG. 1

FIG. 2

FIG. 4

FIG. 3

FIG. 5

FIG. 6

FIG. 7

FIG. 8

FIG. 1 is a top plan view of my new design in the closed position.

FIG. 2 is a front elevational view thereof.

FIG. 3 is a bottom plan view thereof.

FIG. 4 is a side elevational view thereof, the opposite side being substantially a mirror image of the side shown.

FIG. 5 is a rear perspective view thereof.

FIG. 6 is a rear perspective view thereof.

I claim:

The ornamental design for a dressing mirror, as shown and described.
